PETROL AND LIKE LIGHTER

Isaac Joseph Aronowitz, Cambridge, England

Application March 25, 1932, Serial No. 601,093,
and in Great Britain May 11, 1931

5 Claims. (Cl. 67—7.1)

This invention relates to petrol and like lighters of the kind comprising a petrol or like container and a wheel co-acting with a flint and adapted to be operated by the thumb of the hand holding the lighter to ignite a wick.

The object of the present invention is to provide an improved form of lighter in which the operating parts are not liable to be readily damaged and which is convenient to operate and 10 use.

According to the present invention, there is provided a lighter wherein an operating wheel, its associated flint and a wick holder are mounted within a V-shaped depressed portion of the 15 top of the container which extends laterally and opens outwardly of the side walls adjacent one end thereof. The recess is preferably positioned so that a line bisecting the apex angle, which angle is preferably 45°, is parallel with an end 20 of the container. The operating wheel, which term designates a flint-engaging wheel or a separate thumb wheel associated therewith, is preferably mounted with its plane of rotation parallel with, and in close proximity to one face 25 of the V recess, whereby it may be operated by a substantially arcuate movement of the thumb, with the base of the thumb as the centre of the arc.

The lighter is preferably provided with a curved 30 flint housing tube, having its lower end located in the base of the container, the upper portion of the tube being arranged so that a flint carried therein will have its upper end in a plane parallel to the axis of rotation of the wheel with 35 which it engages.

A petrol or like lighter embodying the invention is illustrated, by way of example, in the accompanying drawing wherein:—

Figs. 1 and 2 are front and back elevations 40 of the lighter respectively;

Fig. 3 is a plan thereof, and

Fig. 4 is a detail hereinafter referred to.

Referring to the drawing, a container 1 of substantially rectangular section is formed with 45 a depressed portion 2 in the top thereof, the depressed portion, as shown, being V-shaped, with an apex angle of 45°, the depressed portion being positioned so that a line bisecting this angle is parallel with the side 2¹ of the container.

Mounted within this depressed portion is a 50 knurled operating wheel 3, having its plane of rotation inclined to the horizontal and parallel with the face 7 of the depressed portion. The operating wheel 3 is secured to a flint-engaging or abrasive wheel 4, the said wheels be-

ing mounted on a common inclined pivot 6, which may be in the form of a rod, and which is conveniently secured in position by mounting one end in one side 7 of the depressed portion 2 and the other end in a lug 8, carried by a flint housing tube 9. The tube 9 has its lower end opening into the base 10 of the container, said end being closed by a screw plug 11. The upper portion of the tube which extends through the side 12 of the depressed portion 2, is curved so 60 that the end of the flint will be in a plane parallel to the axis of rotation of the wheel 4, against the periphery of which it is pressed by a spring 13 carried within the tube 9. A wick holder 14, of any suitable form, is provided on 65 the side 12 of the recess 2, in suitable relation to the flint-engaging wheel 4.

The operating wheel 3, which is larger in diameter than the wheel 4, is arranged with a portion of its periphery protruding beyond the 70 side of the container, and is preferably arranged with its under-surface in close relation to the side 12 of the depressed portion 2.

A hood 15 may be provided which is adapted to fit over the wick and flint-engaging wheel 80 4. The hood is carried on an arm 16, the end of which is pivotally mounted in a slotted support 17 secured to the container. The said end of the arm 16 is formed with three faces 18, one of which is normally engaged by a spring- 85 pressed plunger slidable within the slot of the support 17. The faces 18 are so positioned that the spring plunger coacts with the said faces and tends to retain the arm 16 in one of three positions, i. e., closed, vertical, or horizontally 90 extended on the side of the support 17, remote from the wick.

Mounting the operating parts of the lighter in a depressed portion, according to this invention, will tend to protect these parts from damage. Furthermore these parts being practically flush with the surrounding surfaces of the container, the lighter will be more convenient to use, particularly in lighting a tobacco pipe. In 95 this particular connection, the usual super- 100 structure or projecting elements on the known forms of lighters are apt to cause considerable inconvenience.

I claim:—

1. A petrol lighter comprising an inflammable 105 material container having a top provided with a V-shaped depressed portion adjacent one end of said container and extending laterally and opening outwardly of the side walls thereof, an operating wheel rotatably mounted within said 110

depressed portion with its plane of rotation parallel with and in close proximity to one of the inclined surfaces thereof, and a wick holder and a flint holder projecting from the other inclined surface of said depressed portion in operative relation with said operating wheel.

2. A petrol lighter comprising an inflammable material container having a top provided with a V-shaped depressed portion adjacent one end 10 of said container and extending laterally and opening outwardly of the side walls thereof, said depressed portion having an apex angle of substantially 45°, an operating wheel rotatably mounted within said depressed portion with its plane of rotation parallel with and in close proximity to one of the inclined surfaces thereof, and a wick holder and a flint holder projecting from the other inclined surface of said depressed portion in operative relation with said 20 operating wheel.

3. A petrol lighter comprising an inflammable material container having a top provided with a V-shaped depressed portion adjacent one end 25 of said container and extending laterally and opening outwardly of the side walls thereof, said depressed portion being so located that a line bisecting its apex angle will be substantially parallel with the end of the container, an operating wheel rotatably mounted within said depressed portion with its plane of rotation parallel with and in close proximity to one of the inclined surfaces thereof, and a wick holder and a flint holder projecting from the other inclined surface of said depressed portion in operative 30 relation with said operating wheel.

35 4. A petrol lighter comprising an inflammable

material container having a top provided with a V-shaped depressed portion adjacent one end of said container, and extending laterally and opening outwardly of the side walls thereof, an operating wheel including a flint abrasive wheel co-axial therewith and secured thereto rotatably mounted within said depressed portion with its plane of rotation parallel with and in close proximity to one of the inclined surfaces thereof, and a wick holder and a flint holder projecting from the other inclined surface of said depressed portion in operative relation with said abrasive wheel.

5. A petrol lighter comprising an inflammable material container having a top provided with a V-shaped depressed portion adjacent one end of said container, and extending laterally and opening outwardly of the side walls thereof, an operating wheel including a flint abrasive wheel co-axial therewith and secured thereto rotatably mounted with the said depressed portion with its plane of rotation parallel with and in close proximity to one of the inclined surfaces thereof, and a wick holder and a flint holder projecting from the other inclined surface of said depressed portion in operative relation with said abrasive wheel, said flint holder including an upper portion and a curved lower portion extending downwardly through the interior of the container with its lower end opening through the bottom thereof the said upper portion being so located that a flint therein will have its operative surface in a plane parallel to the axial rotation of the abrasive wheel with which it co-acts.

ISAAC JOSEPH ARONOWITZ.
